(57) **CLAIM**

The ornamental design for a cord end stopper, as shown and described.

DESCRIPTION

FIG. 1 is a front view of a cord end stopper of the claimed design.

FIG. 2 is a right side view of the cord end stopper of FIG. 1.

FIG. 3 is a top view of the cord end stopper of FIG. 1.

FIG. 4 is a bottom view of the cord end stopper of FIG. 1.

FIG. 5 is a perspective view of the cord end stopper of FIG. 1; and,

FIG. 6 is a perspective reference view of the cord end stopper of FIG. 1, showing it in use.

The broken line showing of the cord is included for the purpose of illustrating environmental structure and forms no part of the claimed design.
